HENRY CREWDSON, OF WILMINGTON, DELAWARE, ASSIGNOR TO THE VISCOSE COMPANY, OF MARCUS HOOK, PENNSYLVANIA, A CORPORATION OF PENNSYLVANIA

SKEINING MACHINE

Application filed July 20, 1927. Serial No. 207,164.

My invention relates to skeining machines. Among the objects of my invention may be mentioned (1) a mechanism which insures the maintenance of the skein pattern on the reel, 5 regardless of interruption of the drive during skein winding; (2) an improved reel drive; (3) an improved automatic stop for halting the mechanism after predetermined operation; (4) improved traverse operation; 10 (5) various details of improved construction hereinafter described or shown in the accompanying drawings in which—

Fig. 1 is a broken plan view of a machine in which my invention is embodied in one 15 form;

Fig. 2 is a side elevation thereof partially in section;

Fig. 3 is a section on the line 3—3, Fig. 2, drawn to a larger scale;

20 Fig. 4 is a fragmentary side elevation to a larger scale illustrating the automatic stop device;

Fig. 5 is a similar view illustrating the showing of the automatic stop in another position; and

Fig. 6 is a schematic elevation of a reel illustrating the skein pattern.

While my invention may be embodied in a single reel layout, I have indicated portion of 30 a commercial installation in which a plurality of reel units are supported upon a longitudinal channel 15, each unit mounted thereon comprising a pair of reels, one on each side of the channel. The supporting frame of each 35 unit comprises a plate-like casting 16 resting on the channel 15 and having arms 17 and 18 which extend on opposite sides thereof, each arm carrying reels 19 and 20 and their associated mechanisms. Since the mechanisms 40 are alike, it suffices to describe only one.

The drive of each reel is effected by a belt 21 from a pulley on a shaft (not shown) arranged longitudinally beneath the channel 15. Each belt 21 engages a pulley 22 loose on a 45 shaft 23 (Fig. 3) and provided with a pin 24 adapted to engage lugs 25 on a clutch hub 26 sliding on a feather 27 on the shaft 23. At the opposite end of the shaft 23 is pinned, or otherwise secured, gear 28 (Fig. 2) meshing 50 with gear 29 pinned at 30 to the hub 31 of the

reel (19 or 20). The details of the reel construction do not enter into the present invention, but are described in the copending application of Thompson, Ser. No. 201,526, filed June 25, 1927 patented May 28th, 1929, 55 No. 1,715,315.

The clutch hub 26 is displaceable on the shaft 23 against the action of spring 32 by the fork arm 33, the hub 34 of which is fast with the pin 35, supported in the boss 36 of the frame and passing through the fixed cam member 37 and the hub 38 of operating lever 39. The hub 38 of the operating lever is provided with a pair of cam bosses 40 received in corresponding notches 41 in the adjacent 60 face of the block 37. When the lever 39 is swung outward in the direction of the arrow α , the bosses 40 ride out of the notches 41 in block 37, thus displacing the arm 33 sufficiently to shift the clutch hub 26 away from the pulley 22 and thus break the drive engagement of the pin 24 of the pulley with one of the bosses 25 on the hub. A recess 42 formed in the block 37 to one side of the notch 41 affords a slight shoulder which latches the 65 lever in open-clutch position. To re-establish the drive of the reel, lever 39 is moved in the opposite direction, rising out of the recess 42 and dropping into the notch 41 under the stress of the spring 43 engaged between 70 the inner face of the block 37 and the collar 44 on pin 35.

The clutch lever 39 is employed by the operative to halt the drive of the reel during the skeining operation, in case of breakage 85 of the thread, so that the ends of the thread may be knotted and the skeining operation renewed.

During the skeining operation the thread is guided by a traverse motion to form an 90 open diamond pattern 45 (Fig. 6) on the reel, the parts being so related that on successive oscillations of the traverse, alternate courses coincide with substantial precision. The diamond pattern thus formed on the reel facilitates the insertion of the usual lacing thread, 95 provided the openings 46 of the pattern are accurately maintained during the skeining operation. This has not been the case, however, in skeining mechanisms of the present 100

general type heretofore in common use. In such prior mechanisms the arrangement of parts is such that in case of interruption of the reel drive during skeining, in order to 5 repair a broken thread, the initial relation between the traverse and the reel becomes changed, so that after the repair is made and the reel is again put in operation, the delivery from the traverse to the reel is not coincident 10 in its courses with those followed by the thread prior to the interruption. Consequently, the openings 46 in the skein pattern on the reel have been at least partially filled by the new courses. As a result, when the 15 lacing operation is performed, the operative must make openings in the skein for the lacing cord. This is very apt to cause breakage of the thread in the skein.

The present layout so relates the traverse 20 mechanism to the reel that their relation is maintained with precision, regardless of stoppage by the operative during the course of the skein winding.

For this purpose the traverse drive is taken 25 from the reel through gear 47 fast with the reel gear 29. Meshing with the gear 47 is a gear 48 which carries a crank pin 49 engaged by the connecting rod 50. The opposite end of the latter is hinged at 51 to one end of a 30 rock lever 52, the opposite end of which is fast with a vertical rock shaft 53 which passes down through the channel 15. Secured to the rock shaft below the channel is a traverse arm 54, the free end of which supports a bar 55 35 carrying the thread guides 56. In the present instance the reel arms are of sufficient length to permit the formation of two skeins simultaneously thereon. Each traverse bar 55 consequently carries two thread guides 56.

40 It will be noted that when the drive connection from pulley 22 to the reel is halted during the skeining operation, there is no break in the drive connection of the traverse from the reel. Nor is there any alteration 45 in the relation between these parts as has heretofore been the case. Consequently when the drive of the reel is resumed, the traverse arm resumes its motion at precisely the same point, with respect to the reel, at which the 50 operation is halted. Consequently the diamond pattern of the courses on the reel is maintained with precision, and the openings 46 are kept clear of obstruction by floating threads. The lacing cords may therefore be 55 inserted without danger of injury to the skeins.

I also provide an automatic stop for halting the drive of the reel after a predetermined number of revolutions to maintain uniformity 60 in the length of thread wound in each skein. For this purpose I use a clutch operating rod 57, provided, at its clutch-operating end, with a block 58 in which an arcuate slot 59 is provided to receive pin 60 projecting from the 65 upward extensions 61 of the clutch-operating

lever 39. The lost motion engagement between the rod 57 and lever 39 through the pin and slot engagement 59—60 between these parts, permits the manual operation of the clutch lever 39 to open the clutch, without 70 disturbance of the rod 57. It will be noted, however, that when the clutch is manually closed, the pin 60 lies at the outer end of the slot 59. Upon automatic displacement of the rod 57 in the direction of the arrow *y* therefore, the lever 39 is swung in the direction of the arrow *x* and thus opens the clutch. 75

To actuate the rod 57 I provide a spring 62 (Fig. 4) anchored at 63 to the frame, and at 64 to the rod 57. The spring 62 is constantly under tension. The rod 57 is held against the displacing effort of the spring 62, however, by a stop block 65, against which a shoulder 66 on the rod bears. A saddle 67 pressed by spring 68 against the opposite face of the rod, tends constantly to force the shoulder 66 into engagement with the stop block 65. Sufficient play between the rod and the block 65 is provided, however, to permit the shoulder to move against the action of the spring 68 a sufficient distance to clear the block 65, whereupon the spring 62 thrusts the rod 57 in the direction of the arrow *y* to operate the clutch. 80

To free the rod from the block 65 and permit its displacement in the direction of arrow *y* by spring 62 (and thus to open the clutch as above explained) I provide a rotating snail cam 69 fast on shaft 70. As the cam rotates, its nose 71 engages the beveled end 72 of the rod 57 and displaces the latter slightly against the effort of spring 68 to free the shoulder 66 from engagement with block 65. The effort of spring 62 now forces the rod 57 against the cam nose 71 with sufficient pressure to establish a frictional engagement between the rod and cam, such that as the cam continues to rotate in the direction of the arrow *R*, the rod moves therewith, displacing the saddle 67 against the action of its spring 68 until the shoulder 66 of the rod clears the stop block 65. The parts remain in this position until the continued rotation of the cam causes its nose 71 to pass out of engagement with the end of 105 the rod, whereupon the latter drops into the notch 73 of the cam. This notch is of sufficient depth to afford enough longitudinal displacement of the rod to swing the lever 39 to open-clutch position—thus automatically 110 halting the reel drive. After the skeins have been laced and removed from the reel, the operative swings the hand lever 39 inward (opposite to the direction of the arrow *x*), thus pulling the rod 57 outward against the 115 effort of spring 62 until the shoulder 66 re-engages the block 65, simultaneously re-establishing the reel drive. 120

The cam 69 and its shaft 70 are driven from the reel through worm 74 fast on the 125

shaft of gear 48 and meshing with helical gear 75 fast on shaft 76. At the opposite end of the latter is a worm 77 meshing with helical gear 78 fast on the cam shaft 70. Inasmuch as gear 48 is in the train driven from the reel, the rotation of the latter gradually brings the nose 71 of the cam 69 into operation, and the gears are so related that the cam releases the rod 57 to open the reel drive clutch after a predetermined length of skein has been wound on the reel.

The mechanism as a whole is simple, self-contained and compact, free from trappy operation, and difficult to disorder. The gear drive of the traverse and timing mechanism from the reel without interruption or alteration of the position gear connection on the halt of the reel, insures accuracy in the length of the thread wound into the skein, maintains the thread pattern of the skein on the reel, and facilitates the lacing operation without danger of injury to the skein threads. These and other advantages resulting from the invention may be obtained in various modifications which embody the thoughts underlying what I claim as my invention.

I claim:

1. In a skeining machine, a reel, a clutch controlled drive for the reel, a manually actuated clutch operating lever, a trip-released shifting rod having a lost motion connection with said lever, and means for releasing the rod to actuate the clutch after a predetermined reel drive, said means being associated with the reel through permanently engaged mechanism.

2. In a skeining machine, a reel, a clutch controlled drive for the reel, a manually actuated clutch operating lever, a trip-released shifting rod having a lost motion connection with said lever, and means for releasing the rod to actuate the clutch after a predetermined reel drive, said means being associated with the reel through permanently engaged mechanism, and said lever serving to restore the shifting rod to normal position.

3. In a skeining machine, a skeining reel, a clutch operated drive therefor, a manually controlled clutch lever for operating the clutch, in combination with an automatic clutch-opening device including a rod having a lost motion engagement with said lever, a spring for shifting the rod to lever-operating position, a latch for holding the rod inoperative, and means driven by the reel for freeing the rod from its latch after predetermined rotation of the reel.

4. In a skeining machine, a reel, clutch controlled means for driving the same, and an automatic clutch-opening device comprising a rod constantly stressed to open-clutch position, a latch for detaining the rod, and means operated from the reel for freeing the rod from the latch.

5. In a skeining machine, a reel, clutch con-

trolled means for driving the same, and an automatic clutch-opening device comprising a rod constantly stressed to open-clutch position, a latch for detaining the rod, and means operated from the reel for freeing the rod from the latch, together with manually operated means for returning the rod to inoperative position, and simultaneously closing the clutch.

6. In a skeining machine, a reel, clutch controlled means for driving the same, automatically operated means for opening the clutch after predetermined rotation of the reel, said clutch opening means comprising a latch-controlled, spring-stressed, clutch-operating member, and a cam driven with the reels for releasing control latch of said clutch-operating member after predetermined relation of the reel.

7. In a skeining machine, a reel, a drive shaft, and clutch means therebetween consisting of a block adjacent the drive shaft, said block having a notch in its end to engage with a boss on a clutch arm, said clutch arm being adapted to disengage the drive shaft from the reel, in combination with traverse mechanism driven by the reel and in fixed relationship thereto.

8. In a skeining machine, a reel, a drive shaft, and clutch means therebetween consisting of a block adjacent the drive shaft, said block having a notch in its end to engage with a boss on a clutch arm, said clutch arm being manually and automatically operable adapted to disengage the drive shaft from the reel, in combination with traverse mechanism driven by the reel and in fixed relationship thereto.

In testimony whereof I have signed my name to this specification.

HENRY CREWDSON.
